UNITED STATES PATENT OFFICE.

JOHN R. BURRESS, OF ARLINGTON, TEXAS, ASSIGNOR, BY DIRECT AND MESNE ASSIGNMENTS, TO W. A. CEASE AND W. A. DAVIS, BOTH OF TULSA, OKLAHOMA.

AUTOMATIC RAILWAY GATE.

Application filed July 9, 1924. Serial No. 724,946.

This invention relates to certain new and useful improvements in an automatic railway gate and particularly to that type wherein a highway crossing is automatically closed to vehicular and other traffic upon an approaching train entering the immediate block.

The primary object is to provide a railway crossing gate which will be efficient, durable and safe in operation and with this in view the invention resides in an improved gate construction tending toward greater safety at the grade crossing; an improved mechanism for operating the gate, upon the entry of a train into the immediate block; and an improved electrical block system for effecting automatic control of the gate operating mechanism.

The invention further resides in the salient features of construction and the arrangements and combinations of parts hereafter described and claimed, reference being made to the accompanying drawings wherein:

25 Figure 1 is a fragmentary elevation depicting the relation of the parts when the gate is operative;

Figure 2 is a similar view showing the gate inoperative;

30 Figure 3 illustrates the leverage system slightly modified as to the application to power, connecting the two gates on opposite sides of the track;

Figure 4 is a detailed section on line 4—4 of Figure 1;

Figure 5 illustrates diagrammatically the electrical control and circuit system embodied in the present invention;

40 Figures 6, 7 and 8 and 9 are detailed views of the gate per se; and

Figure 10 is a perspective view disclosing a partial application of the invention with the source of operating power applied intermediate the gates, as indicated in Figure 3.

45 Figure 11 is a fragmentary plan view of the gate supporting post, with bracing means.

Referring more in detail to the drawings, the automatic or train-controlled gate mechanism is mounted on a base or foundation 1, and comprises an electric motor 3, the shaft 4 of which is connected by a flexible coupling 5 to a reduction gearing in the housing 6 which gearing, in turn, is connected to a

further reduction gearing within a larger housing 2. The reduction gearing is of such a character that a small motor may efficiently perform the heavy work of swinging the gates. From the gear casing or housing 2 a driven shaft 9 protrudes and carries a fixed cam wheel 8 adapted to be rotated very slowly. The cam wheel is here illustrated as having three lobes or cam projections each having an arcuate rise 8' and an abrupt drop 8" over which operates a follower roller 12. The latter is carried on one end of the lever 11 which is intermediately pivoted at 10 and has its opposite or lower end pivoted to a link 14, as at 15. By means of spring 16 the link is connected to a second link 17, these three elements constituting a yieldable or resilient, composite link for connecting lever 11 to one arm 18 of the bell crank 22 as at 19. The arm 20 of said bell crank is pivotally connected, as at 21, to a link 70 (see Figs. 3 and 10). In Figs. 1 and 2 the operating power is delivered direct to one of the gate posts by link 17, while in Figs. 3 and 10 the power is applied intermediate the gates, as to a bell crank 71 connected to the opposite end of the link 70. In the latter case the bell crank 22 is replaced by a single arm 72 to which the link 70 is connected. The bell crank 71 is connected across the highway, by link 73, to a second bell crank which in turn, is coupled to crank arm 74 of the companion gate post, by link 75.

Each gate post 24 has its lower end journaled in bearing 23 and its upper end journaled in a bearing 26 which is itself supported by a bracket 28 from a stationary upright 13, the latter being braced at 27. A disk or plate 76 is fixed on each gate post to rotate therewith and is equipped with a fixed stop 77 and a shear-off stop 78.

A sleeve 25 is journaled on the gate post and rests upon the said plate for rotative movement. This sleeve has a gate member 30 projecting therefrom and this member is braced by a strut 29 leading to the top of the post. A coiled spring 79 encircles the gate post with one end fixed thereto and its opposite end to the gate member to constantly urge the latter against the stop 77. Should an obstruction encounter the gate during closing thereof, the gate may yield by rotating about the post until it engages the post 78. If further swinging of the gate 110

is required to clear the obstruction, the gate member 30 will break or shear off the preferably wooden pin 78. A sign or signal 31 may be placed on the gate to be conspicuous.

5 The gate preferably consists of a fixed inner section and a flexible outer end portion. The flexible outer end is here depicted as being a thin strip of spring steel, or other resilient material, 56 faced on one side as 10 indicated in Fig. 8, or on both sides, as in Figs. 6, 7 and 9. The facings are secured in place by bolts 58 and 60. The back or inner facing consists of a series of strips or blocks 57, preferably of wood, having their 15 squared ends abutting and capped with metal reinforcing sheathing 64. The front face is also preferably covered with wooden facing blocks 55, their ends being spaced apart as at 63 and inwardly beveled to define 20 vertical edges 80 over which the spring strip 56 will bend. The edges 80 are spaced apart a considerable distance to avoid a too abrupt bending of the strip. To further prevent the strip from being bent out of shape and 25 from sagging under a lateral bending pressure, the several, defined bending points are individually reinforced by the addition of a short spring strip 65, toward the outer or tip end of the gate, and by addition of 30 plural strips 65 and 65' toward the pivot end of the gate, as shown in Fig. 8. The free end of the gate terminates in a loop or ring 62, secured thereon by bolts 61, while the inner end of the yieldable section of the gate 35 is secured to the rigid inner portion 53 by bolts 54.

The several electrical connections, for effecting the automatic closing and opening of the gates, are diagrammatically represented in Fig. 5 wherein the track is composed of rails 1^a and 3^a the latter having sections electrically separated by insulations *a* and *b* thus dividing the said rail into a separate approach block for either direction 45 of travel. A signal battery 2^a is electrically connected to each approach block by wires 2^a and 2^c, resistance 2^b and wire 2^c. Adjacent insulation *b*, or at the grade crossing, electrical connections are made by wires 4^a 50 and 5^a to relay magnets 6^a and 7^a, which relays are of the standard interlocking relay type used by railroads of today. Their respective contacts 9^a and 10^a are connected by wire 13^a and 8^a to a repeater magnet 14^a, wire 15^a connecting the latter to a storage battery 11^a which is itself connected to the fixed contacts of the relays by wire 12^a.

60 Normally, in practical operation, the time taken to completely close the highway with this machine is approximately twenty (20) seconds, during which time a train might enter at points *a*, reverse and leave the block in less than twenty seconds, thereby stopping the motor and leaving the gates only

partly open. From Figs. 1 and 2 it can be seen that the gates cannot swing back to their normal position until the operating lobe of the cam takes the position shown in Fig. 2. Therefore, there is placed in the 70 circuit a "master" switch 40 and 41 which prevents the mechanism stopping prematurely. This switch is mounted on lever 33 and when the cam has moved a fraction, switch lever 40 will drop from it, and make 75 contact with 41, which makes a complete circuit to repeater magnet 14^a from storage battery 11^a, through wires 12^a, 12^b, contacts 41 and 40 wires 35^a, 8^a, and 15^a. It will therefore be observed that this keeps the 80 motor operating regardless of the position of contacts 9^a and 10^a, until the gates are across the highway, then switch lever 33 will fall from the lobe of the cam and separate points 40 and 41, and if contacts 9^a and 10^a 85 are held up (as would be the case if the train had left the block) the circuit will be broken to repeater magnet 14^a allowing the motor to operate and release the gates, as 90 above set forth.

Signal lights 17^a may be placed so as to be seen on approaching the gates and burn throughout the operation of the mechanism. Flood lights 32^a may be placed in a position to flood the stop sign 31. Red lights 32^b 95 may be placed near the center of gate 30 so as to be seen when approaching the gates if the gates are across the highway. The lights 32^a and 32^b may be controlled by an automatic switch 29^a and 30^a to operate to 100 turn them on when the gates are halfway open and turn them off when they swing back to their normal position. Rail 1^a is electrically connected throughout or for a given distance. Rail 3^a is also electrically connected from insulation *a* to insulation *b*, which is placed at the point where the street or highway crosses the railroad.

Signal battery 2^a is connected to rail 1^a through wire 2^c, resistance unit 2^b and wire 110 2^c, and to rail 3^a through wire 2^a. At insulation *b* connection is made from rail 3^a to relay magnets 6^a and 7^a, through wire 4^a, and from rail 1^a through wire 5^a.

Current normally flows through the relay magnets from the signal battery which energizes the relay magnets, causing them to lift contact points 9^a and 10^a and hold them in such position.

Now should a train enter the block to the right signal battery 2^a will be short-circuited from relay 7^a which allows contact points 10^a to fall and touch the fixed contacts or wires 12^a which complete a circuit from storage battery 11^a to repeater magnet 14^a through wires 12^a, 13^a, 8^a and 15^a, which energizes the repeater magnet 14^a. This lifts the magnet contact points 20^a which makes contact with wire 19^a and completes a circuit to motor 3 from storage battery 11^a.

through wires 15^a, 18^a and 40^a, contacts 20^a, wire 19^a, switch 33, contacts 34 and 35 switch lever 36, wire 23^a brushes 26^a and 27^a, and wire 25^a, thereby starting armature 24^a of the electric motor. As the motor 3 is started, cam 8 will also turn, which applies pressure against roller 12, moving it forwardly to rock the bar 11 and pull the resilient link 14, 16, 17 to swing the gates to the position shown in Fig. 10, thereby closing the highway.

From Fig. 1 it will be noted that the contacts 34 and 35 are carried respectively on the levers 33 and 36 which are pivotally mounted in a support 32 so that their free ends may ride on the curved face 8' of one of the lobes of cam 8. When the gates have moved to closed position the lever 33 rides off the cam and effects a separation of the contacts 34 and 35 and a breaking of the circuit to the motor which stops the motor with the gates 30 across the highway, where they are held, by the pressure of the cam against the lever 11, until the last coach passes insulation b.

The contacts 9^a and 10^a are alternately engageable by a pivoted arm as in the usual interlocking type of relay, whereby to permit direction of operation, therefore when a train enters the block through the right insulation a, the contacts 10^a are affected to obtain proper current through the motor. The contacts 9^a remain inoperative because the pivoted arm, common to all type of interlocking relays used in railway equipment is so placed as to prevent contact. It will be understood that the contact point 9^a remains in such inoperative position until the last set of trucks pass the insulation a at the left of the signal, or completely out of the block. Now, when a train enters from the opposite direction, the effect upon the contacts 9^a and 10^a is identical, except that contact 9^a is operative while the contact 10^a remains inoperative.

It will be understood that the points 34 and 35 are normally in contact when the gates are open to the highway, and should a train enter the block from either direction, the cam 8 is started to rotating slowly. Thus, lever 33 is first lifted for the purpose of placing points 37 and 38 together, preparatory to completing an opening circuit after the train passes insulation b. In Figure 1, it will be seen that lever 33 has dropped from the lobe of the cam 8, thus separating points 34 and 35, which breaks circuit to the motor, such separation being caused by the lever 36 remaining on the lobe of the cam as shown, which position is maintained until the last set of trucks pass insulation b. In brief, when the train enters the first block, the motor closes the gate and stops, and after the last truck passes insulation b, the motor is again started to open the

gate. Contact is again established to the motor by the passage of trucks, through contacts 37 and 38, thereby again revolving the cam, until such time as the lever 36 falls from the lobe of the cam and takes the position shown in Figure 2. The contacts 40 and 41 are pivoted as previously mentioned, on lever 33, and are adapted to function, in emergency cases, that is, to prevent the gate from stopping in incomplete stages of operation, should a train enter and back out of the block before the established operating time for the mechanism has been depleted.

When the last set of trucks pass insulation b energy is again restored to relay magnet 7^a by the flow of current from signal battery 2^d which again lifts contact points 10^a, breaking the circuit to repeater magnet 14^a thus permitting contact points 20^a to fall to make contact with wire 38^a. This again completes a circuit to motor 24^a from storage battery 11^a through wires 15^a, 18^a, 40^a, contacts 20^a, wire 38^a, through switch 39, 38, 37, 36, wires 23^a brushes 26^a and 27^a and wire 25^a. The motor will operate until lever 36 takes the position of Fig. 2 by riding off the cam which breaks the circuit to the motor at points 37 and 38, at the same time moving the point of the cam below the outside edge of roller 12 whereby the roller will drop toward the axis of the cam to swing the gates open. To assist the opening movement a weight 81 is guided over a bracket 82 on upright 13 and connected by a cable 83 to the brace 29.

It will be noted that the outer portion of the gates yield outwardly to permit the escape of anyone having been caught between them as they were closing. Should either of the gates be struck, it will yield until it engages the stop pin 78 and if the impact is excessive the pin will be sheared off to avoid damaging the gate and to permit it to yield through a greater arc against the tension of the spring 79.

The switch 33, 36 is in parallel with switch 40, 41 the former being closed in the normally open position of the gates when it will be noted that the switch 40, 41, is opened.

What is claimed is:

1. An automatic railway gate comprising a movable body which is arranged to be swung laterally across a highway, a movable cam having a gradual lift and an abrupt drop, means operable over the cam lift for closing the gate body, said means remaining on the lift portion to hold the body closed, a resilient connection between said last mentioned means and said gate, and gate opening means operable to move the cam to cause said first means to ride off the lift portion onto the drop portion thereof.

2. An automatic railway gate comprising a movable body which is arranged to be

swung laterally across a highway, a movable cam having gradual lifts and abrupt drops, means operable over one of the cam lifting portions for closing the gate body, means for retaining said first mentioned means on the lifting portion for closing the gate body, resiliently tensioned means for urging the gate body to open position, and means for moving the cam lift portion from under said first means to permit the same to fall into one of the abrupt drops.

3. An automatic railway gate comprising a laterally movable gate body, gate operating means including a movable cam having lift portions and drop portions for respectively closing and releasing the gate body, and means controlled by the cam for permitting the gate closing means to operate.

4. An automatic railway gate comprising a laterally movable gate body, gate operating means including a movable cam having lift portions and drop portions for respec-

tively closing and releasing the gate body, a motor for moving the cam, and switch means under the control of the cam for stopping 25 the motor.

5. An automatic railway gate comprising a laterally movable gate body, means for causing said gate body to open, a movable cam lift and drop portions for respectively 30 closing and releasing the gate body, a motor for moving said cam, a switch for starting the motor to close the gate, a cam-controlled switch for starting the motor, a cam-controlled switch for insuring maintenance of 35 the motor circuit, said cam switches being adapted to be opened by the cam when the gate is closed, and a second switch for starting the motor for permitting the gate to open when the circuit to the first switch is 40 opened.

In testimony whereof I affix my signature.

JOHN R. BURRESS.
